UNITED STATES PATENT OFFICE.

JAMES C. BALL, OF STAR HILL, LOUISIANA.

DESIGN FOR A CUTTER ATTACHMENT FOR PLOWS.

SPECIFICATION forming part of Design No. 27,434, dated July 27, 1897.

Application filed May 19, 1897. Serial No. 637,293. Term of patent 14 years.

To all whom it may concern:

Be it known that I, JAMES C. BALL, a citizen of the United States, residing at Star Hill, in the parish of West Feliciana and State of Louisiana, have invented and produced a new and original Design for a Cutter Attachment for Plows, of which the following is a specification, reference being had to the accompanying drawings, forming a part thereof, in

10 which—

Figure 1 is a perspective view of a cutter attachment for plows embodying the features of my design, and Fig. 2 is a plan view of the attachment.

15 The design consists in the novel grouping of the following elements, in which is represented a blade A, one end *a* whereof is curved

and appears with a sharpened edge, while the opposite end is wider and of somewhat rectangular form in cross-section. The wider 20 end of the blade is apparently connected by bolts *b* to a plate B, located above it. An arm C is projected at an angle from the back portion of the blade A at a point between its ends, and the arm C also appears attached to 25 a plate D by means of bolts *d*.

I claim—

The design for a cutter attachment for plows herein shown and described.

JAMES C. BALL.
